(57) **CLAIM**

The ornamental design for a food container, as shown and described.

DESCRIPTION

FIG. 1 is a perspective view of the food container;
FIG. 2 is a front view of the food container of FIG. 1;
FIG. 3 is a back view of the food container of FIG. 1;
FIG. 4 is a left side view of the food container of FIG. 1;
FIG. 5 is a right side view of the food container of FIG. 1;
FIG. 6 is a top view of the food container of FIG. 1; and,
FIG. 7 is a bottom view of the food container of FIG. 1.
Color and texture may or may not form part of the claimed design without departing from the design disclosed. The inventors anticipate that the invention can be any part, portion, element, or combination of elements of the depicted design.

The food container is typically used to hold and serve food.
The food container comprises a base and a removable lid.
